CLAIM

The ornamental design for a dispenser, as shown and described.

DESCRIPTION

FIG. 1 is a perspective view of the dispenser showing our new design with the pump head in broken lines;

FIG. 2 is a front elevation view thereof.

FIG. 3 is a rear elevation view thereof.

FIG. 4 is a left side elevation view, the right side elevation view being a mirror image thereof.

FIG. 5 is a top plan view thereof; and,

FIG. 6 is a bottom plan view thereof.

The broken line showing of the interior of the bottom of the container, the container threads and the pump head is for illustrative purposes only and forms no part of the claimed design.
